Primary Examiner — Rosemary K Tarcza*(74) Attorney, Agent, or Firm* — Rader, Fishman & Grauer PLLC**CLAIM**

The ornamental design for a battery, as shown and described.

DESCRIPTION

FIG. 1 is a perspective view of a battery showing our new design;

FIG. 2 is a front elevational view thereof; and,

FIG. 3 is a top plan view thereof.

The broken lines shown in the drawings are included for the purpose of illustrating environmental structure and form no part of the claimed design.

1 Claim, 3 Drawing Sheets**FIG.1**

FIG. 2
